EXTENSIBLE BAND

Filed Feb. 2, 1929

FIG. 1.

FIG. 3

INVENTOR
VICTOR GUINZBURG
BY *E. Levinsohn*
ATTORNEY

UNITED STATES PATENT OFFICE

VICTOR GUINZBURG, OF NEW YORK, N. Y., ASSIGNOR TO I. B. KLEINERT RUBBER COMPANY, OF NEW YORK, N. Y.

EXTENSIBLE BAND

Application filed February 2, 1929. Serial No. 337,058.

This invention relates to an extensible waist band adapted to be attached to the body embracing portion of a garment and has reference particularly to a band made up of rubber coated knitted fabric which is so folded upon itself and then treated, that one edge is rolled and perfectly smooth, the mid portion is two ply and adhered together making it capable of longitudinal expansion only, and the sides opposite the roll are unattached and intended to embrace opposite sides of the end of the garment which may be gathered or otherwise arranged at the body embracing portions to allow for the expandable band.

It is to be noted that the present invention is a further development of my improved belting which forms the subject matter of my co-pending application for Letters Patent, filed December 7th, 1928, Serial No. 324,429.

This invention has for its object to provide an extensible band for garments, which is highly elastic in one direction and which may be made up of the self material of the garment and so easily and efficiently applied to the garment as to greatly reduce the cost of manufacture of such articles, for example, as undergarments, hosiery and knitted outer garments.

One embodiment of my invention is illustratively exemplified in the accompanying drawings, in which Figure 1 is a side elevational view of a length of waist band constructed in accordance with the invention; Figure 2 is a substantially transverse sectional view of the band taken on lines 2-2 of Figure 1; and Figure 3 is a perspective view of the band applied to the body embracing portion of a garment.

Referring now to the drawings, 10 denotes a piece of knitted or loosely woven material capable of stretching in one direction only, longitudinally. One face of the material is coated with a thin layer of rubber 11. The process of applying a layer of rubber of this character is well known in the art and requires no further explanation here. The product for example may be what is commercially known as rubber coated stockinette.

As illustrated particularly in Figure 2, the band is formed by folding a strip of this

coated stockinette longitudinally thereof so as to bring its side edges together, the rubber coated faces being arranged on the inside and in contact with each other. The folded portion is allowed to roll, the mid portion is formed into an integral strip by applying a knurled roller to the outer surfaces before the band is subjected to a vulcanizing treatment. As explained in the aforesaid application, this treatment causes the two adjacent rubber surfaces to knit and adhere together very closely and to particularly become integral after the same has been vulcanized. If desired, of course, the roll at the folded edge may be dispensed with and the entire strip, except only the free ends 12, may be formed into an integral strip.

According to the present invention, the adhesion is carried out only in the mid portion of the band, the two ends 12 forming the marginal portions thereof, as illustrated in Figure 2, being allowed to remain separated. It will be clearly understood, of course, that in rubber coating the mid portion of the band, the two ends 12 forming the marginal portions may, if desired, be left free from coating.

In the manufacture of garments utilizing my improved bands, the end to receive the band is gathered or allowed to remain straight and inserted between the surfaces of the two separated ends 12, as illustrated in Figure 3. The ends 12 are then attached to the opposite sides of the garment material by any convenient means, as for example a row of stitching 13, which must of necessity be capable of stretching with the band.

A garment in which my improved band is incorporated has all the advantage of one in which elastic webbing is used as a support without the necessity of forming a hem in the garment and inserting the webbing therein which is the usual practice.

It will be understood from the foregoing that by means of my invention my improved band may be made as shown in Figure 2, where the entire surface of one side of the banding material has been rubber coated and the center portion at the fold is rolled. It will also be understood that my invention contemplates

a banding made of material one side of which has been entirely rubber coated and the roll at the folded edge of which may be dispensed with, so that all but the free ends 12 have been 5 made integral as hereinabove described. My invention comprises as well, banding so made that one side of the banding material has been completely coated except as to the edges 12 thereof from which the coating may be omitted. 10 In which construction the folded end may be left rolled, if desired, or the roll at the folded end may be disposed with.

Having described my invention, what I claim is:

- 15 1. As an article of manufacture, a continuous strip of textile material, rubber coated throughout its width and folded longitudinally thereof, the fold forming a soft unfilled tube, the rubber of the two layers at the longitudinal mid portion being integrally adhered together, and the layers along the edge opposite the fold being open.
- 20 2. As an article of manufacture, a continuous strip of textile material rubber coated on one side and throughout its width, and folded longitudinally thereof with the uncoated face on the outside, the fold forming a soft unfilled tube, the rubber of the two layers being integrally adhered along the longitudinal mid portion, and the marginal portions of the layers being splayed.
- 25 3. An article of manufacture as claimed in claim 2, in which the rubber surfaces of the splayed marginal portion of the layers are unvulcanized.

In testimony whereof he has affixed his signature.

VICTOR GUINZBURG.
